UNITED STATES PATENT OFFICE

139,082

DESIGN FOR AN AIRPLANE HANGAR

Wilbur B. Larkin, Kansas City, Mo., assignor to
Butler Manufacturing Company, Kansas City,
Mo., a corporation of Missouri

Application February 15, 1944, Serial No. 112,594

Term of patent 14 years

(Cl. D13—1)

To all whom it may concern:

Be it known that I, Wilbur B. Larkin, a citizen of the United States, residing at Kansas City, in the county of Jackson and State of Missouri, have invented a new, original, and ornamental Design for an Airplane Hangar, of which the following is a specification, reference being had to the accompanying drawing, forming part thereof, in which

Fig. 1 is a front perspective view of the hangar showing my design,

Fig. 2 is a rear perspective view showing my design.

I claim:

The ornamental design for an airplane hangar, as shown.

WILBUR B. LARKIN.
